(57) **CLAIM**

The ornamental design for a base for a mobile stand, as shown and described.

DESCRIPTION

FIG. 1 is an upper-right-front perspective view of a base for a mobile stand in accordance with the present design; FIG. 2 is a lower-left-back perspective view of the base for a mobile stand shown in FIG. 1; FIG. 3 is a top plan view of the base for a mobile stand shown in FIG. 1; FIG. 4 is a bottom plan view of the base for a mobile stand shown in FIG. 1; FIG. 5 is a front view of the base for a mobile stand shown in FIG. 1; FIG. 6 is a back view of the base for a mobile stand shown in FIG. 1; FIG. 7 is a right side view of the base for a mobile stand shown in FIG. 1; and, FIG. 8 is a left side view of the base for a mobile stand shown in FIG. 1. The broken line showing of an aperture is for the purpose of illustrating portions of the base and forms no part of the claimed design.

1 Claim, 6 Drawing Sheets
